CLAIM

The ornamental design for a mobile phone, as shown and described.

DESCRIPTION

FIG. 1 is a front elevation view of a mobile phone, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front-left perspective view thereof;

FIG. 8 is a front-right perspective view thereof;

FIG. 9 is a rear-right perspective view thereof; and,

FIG. 10 is a rear-left perspective view thereof.

1 Claim, 9 Drawing Sheets
